United States Patent Office

Des. 195,601
Patented July 2, 1963

195,601

PACKAGING CONTAINER

John Donald Bostrom, Niles, Ill., assignor to Poster Packaging, Inc., Chicago, Ill., a corporation of Delaware

Filed Mar. 8, 1961, Ser. No. 64,184

Term of patent 14 years

(Cl. D58—11)

FIG. 4

4

4

FIG. 3

The top for the container which is shown in broken lines is plain.

The essential features of the design are shown in full lines.

I claim:

The ornamental design for a packaging container, as shown and described.
